(57) **CLAIM**

The ornamental design for a center console for an automobile, as shown and described.

DESCRIPTION

FIG. 1 is a front elevational view of a center console for an automobile in accordance with my new design;

FIG. 2 is a top plan view of the center console in accordance with my new design of FIG. 1;

FIG. 3 is a bottom plan view of the center console in accordance with my new design of FIGS. 1 and 2;

FIG. 4 is a left side elevational view of the center console in accordance with my new design of FIGS. 1 to 3;

FIG. 5 is a right side elevational view of the center console in accordance with my new design of FIGS. 1 to 4;

FIG. 6 is a front, left perspective view of the center console in accordance with my new design of FIGS. 1 to 5;

FIG. 7 is a rear, right perspective view of the center console in accordance with my new design of FIGS. 1 to 6; and,

FIG. 8 is a rear elevational view of the center console in accordance with my new design of FIGS. 1 to 7.

The inside surfaces of the center console form no part of the claimed design since the inside surfaces are hidden when the center console is mounted to an automobile.

A second embodiment of our new design is identical to the first embodiment. The second embodiment of our new design includes the mirror image of the center console shown in FIGS. 1 to 8.
